UNITED STATES PATENT OFFICE.

ALFRED SMITH, OF LA MADELEINE-LEZ-LILLE, FRANCE.

STRIPPING APPARATUS FOR CARDING MACHINES AND THE LIKE.

1,424,598.

Specification of Letters Patent. Patented Aug. 1, 1922.

Application filed May 7, 1920. Serial No. 379,612.

To all whom it may concern:

Be it known that I, ALFRED SMITH, a subject of the King of Great Britain, and a resident of 160 Rue Faidherbe, La Madeleine-lez-Lille, Department of Nord, France, have invented new and useful Improvements in Stripping Apparatus for Carding Machines and the like (for which applications for patents have been made in France, May 5, 1919, and Great Britain, June 24, 1919), of which the following is a specification.

This invention relates to a suction operated stripping apparatus for carding machines and the like.

Arrangements of this kind have already been proposed in which a suction nozzle moves continuously forward in front of the casing of the carding cylinder and parallel to a generatrix of the cylinder. This arrangement presents the disadvantages of creating an interruption of continuity in the sliver and of therefore preventing the latter from keeping itself adequately supplied with the raw material, in particular at the ends of the casing.

The stripping device forming the subject of the present invention enables these disadvantages to be avoided; it consists essentially in a stripping tube placed as close as possible to the casing of the carding cylinder, this tube being provided with a longitudinal suction slit which extends over the whole width of the casing, and the slit being uncovered by means of a suitable device at sections located at a certain distance apart, so that the stripping takes place at sectors which are not adjacent but separated a suitable distance in such a way that the evenness of the sliver is completely ensured more especially at the ends of the casing.

For this purpose the stripping tube comprises an inner tube fitting freely therein, and receiving a rotary motion from the countershaft of the carding machine; this inner tube is provided along its generatrices with slits of short length and of width equal to that of the slit in the stripping tube. These slits in the inner tube are staggered in relation to one another, forming a kind of helix or winding upon the tube, in such a way that those which are located in line upon the same generatrix of the tube, that is to say those which uncover the slit in the stripping tube at the same time, are located at a suitably chosen distance apart.

At the ends the slits are shorter so as to ensure the continuity of the sliver at this part, where it is propelled only on one side by the material contained in the casing and not yet stripped, since there is no material beyond the extremities.

In addition, there is provided a starting and stopping device controlled by the countershaft of the carding machine, which allows the stripping operation to be rendered completely automatic and dispenses with any intervention of an operative.

One example of carrying out the subject of the invention is represented on the annexed drawing, in which:

Figure 1 shows a longitudinal section of the suction tube of the stripping device.

Figure 2 is a longitudinal section of the inner tube.

Figure 3 is a diagrammatic cross section of the inner tube showing the distribution of the slits, the section being taken irregularly through the latter.

Figure 4 is an axial section of a larger scale of the suction-tube and the inner tube.

Figure 5 is an elevation of the controlling device for the stripping apparatus.

Figure 6 is a diagram representing a carding machine provided with the stripping apparatus in accordance with the present invention.

Upon the frame *a* of the carding machine is fixed the suction-tube *b* of the stripping device located as close as possible to the casing of the carding cylinder *c* (see Figure 6). This tube is provided on the side facing the casing with a longitudinal slit *b*¹ (see particularly Figure 1), which covers the whole width of the casing of the cylinder. Within this tube there revolves freely a second tube *d* (Figures 2, 3 and 4) provided with a series of rectangular slits *d*¹, the width of which corresponds to the slit *b*¹ in the tube *b*. These slits are arranged along a certain number of generatrices of the tube and form a kind of coil as shown in Figure 2. If placed end to end, these slits fully cover the whole width of the casing, but since only the slits located upon one and the same generatrix of the tube *d* are presented at one time in front of the longitudinal slit *b*¹ in the exterior of tube *b*, the suction takes place at several sectors situated a certain distance apart, which allows the casings again to take up the raw material in the cleared sectors be-

fore the stripping of any adjacent sector is effected.

In order that the ends of the casings may retain with certainty the continuity of the sliver after the stripping, the slits d^1 in the inner tube are of different lengths, being shorter towards the ends than in the center, as seen in Figure 2. In these conditions, the material existing in the casing adjacent to the sector which has just been stripped is sufficient to propel the fresh material filling up the cleared sector; in this way the continuity of the sliver is maintained even at the extremities, although the latter are only propelled on one side. In the case of the slits located towards the middle of the casing, the slits may be longer, because the fresh material filling up the cleared sectors is propelled on both sides by the material filling the adjoining uncleared sectors.

The tube b is connected by a suction pipe b^2 to a collecting receptacle provided with filters in communication with a vacuum pump.

The starting and automatic stopping of the device is effected automatically by the controlling means represented in Figure 5.

The countershaft e of the carding machine, which regulates the supply of raw material, controls by the skew gears e^1 e^2 , and the gear wheels e^3 , e^4 an endless screw f , having a double thread, one right-hand f^1 and one left hand f^2 , which is journaled in supports f^3 secured upon the frame a of the carding machine.

Upon the double-threaded screw f there is displaceable a collar g having a toggle g^1 which engages the threads; this collar is prevented from turning by a guide g^2 provided with a slide-way in which travels a claw g^3 integral with the collar. The latter has therefore a continuous up and down movement, the toggle g^1 engaging in turn first in the thread f^1 and then in the thread f^2 . When the collar g arrives at the top of its stroke, it raises a movable plate h which can slide upon the spindle f and carries a tappet h^1 adapted to engage a tappet h^1 carried by a disc k mounted loose upon the spindle f . This disc is provided with teeth k^2 arranged in groups at suitable distances apart; these teeth mesh with a pinion l which rotates the inner tube d , and the distance between the teeth is chosen in such a way that the interval of time between the meshing of two successive groups of teeth with the pinion l of the inner tube d may be sufficient to allow the cleared sectors to become refilled with raw material before the clearing of the other sectors takes place. When the collar g has completed one revolution, that is to say after all the teeth k^2 have been in contact with the pinion l of the inner tube, it descends again and the movable disc h falls down to

its original position; the inner tube d ceases to revolve after having made one complete revolution for the clearing of the carding machine. There is thus obtained in this way an intermittent control of the stripping device which is completely automatic.

In order to be able to vary, according to the quality of the raw material, the space of time between two successive strippings there may be arranged a stop piece regulating the up and down movement of the collar upon the double-threaded screw.

It will be understood that the invention is not limited to the form of construction which has been described and given by way of example; thus the provision of an inner tube for uncovering the slit in the stripping tube by sectors might be replaced by any other arrangement allowing the suction and therefore the clearing to be effected intermittently as regards the non-adjacent sectors of the casing of the carding cylinder. In the same way the controlling device, for starting and stopping the stripper, might be replaced by any other suitable arrangement for the same purpose.

This method of stripping which is applicable with advantage to all textile machines, presents moreover in addition to those already pointed out, the advantage of allowing the grinding and adjustment of the cards without requiring them to be taken down.

The same stripping arrangement may be applied to the doffing cylinder, its operation being effected by the same controlling device by allowing the stripping of the doffer to take place at half-time in relation to the stripping of the cylinder.

Having now particularly described and ascertained the nature of my said invention and in what manner the same is to be performed I declare that what I claim is:—

1. A suction operated card-stripping or cleaning device, comprising a stripping tube adapted to be arranged against the casing of a carding cylinder, and having a longitudinal slit extending over the whole width of the casing, and distributing means for permitting the exertion of the suction effort through said slit only at predetermined laterally spaced areas at successive time intervals so that the stripping of the card is effected at non-adjoining areas, and the evenness of the sliver thus maintained.

2. The construction specified in claim 1, comprising as its distributing means a tube freely revoluble within the stripping tube and provided along a certain number of its generatrices with short slits adapted to register with the slit in the stripping tube and staggered in relation to each other so as to form a kind of spiral upon the inner tube.

3. The construction specified in claim 1, comprising as its distributing means a tube rotating within the stripping tube and being

provided with slits of unequal length, being shorter towards the extremities than towards the middle of the tube, in order that at the former positions the sliver may be propelled 5 with certainty by the raw material existing in the adjacent area not yet cleared.

4. The combination with the suction striping device specified in claim 1, of an automatic stopping and starting means therefor, 10 comprising a clutching and declutching mechanism, and means driven by the carding machine for operating said clutch periodically to effect the operation of the distributing means automatically at regular and suitably chosen intervals of time, according to 15 the qualities of the raw material.

5. The combination with the suction striping device specified in claim 1, of automatic starting and stopping means therefor, comprising a clutching and declutching mechanism for controlling the operation of the distributing means, a clutch operating member, and an endless double-threaded screw imparting a to and fro movement to said operating member, and means associated with 20 25 the carding machine for rotating the same.

In testimony whereof I have signed my name to this specification.

ALFRED SMITH.
